UNITED STATES PATENT OFFICE.

WILLIAM H. GELBAUGH, OF TACOMA, WASHINGTON.

TRIPLE-MOTION SASH AND HINGE FOR CASEMENT WINDOWS.

Application filed May 25, 1927. Serial No. 193,997.

My invention relates to casement windows more particularly in which the sash is designed to swing inward. The object of the improvement is to provide a casement sash 5 so hung to swing inward and when closed to be rain-proof and dust tight; and a further object is to provide a casement window in which a window screen may be hung on the outside and not interfere with the operation of the casement sash.

I attain these objects by means of the mechanism illustrated in the accompanying drawing, in which—

Fig. 1 is a partial inside view of a casement window with the sash closed from the inside; Fig. 2 is a vertical section of Fig. 1 on the line 2—2; Fig. 3 is the same vertical section with the sash lifted up preparatory to opening inward; Fig. 4 is the same with 10 the sash swung open and back parallel with the wall and showing the triple motion hinges; Fig. 5 is a horizontal cross section of Fig. 1 on the line 5—5; Fig. 6 is a front view and Fig. 7 is a side view of the sash 15 lift and adjuster for the casement window; Fig. 8 is a radial friction stool plate on which the rubber foot of the sash adjuster is to seat; Fig. 9 is a front view, and Fig. 10 is a top view and Fig. 11 is a back view of 20 the spring actuated hinge bolt to stay the sash when lifted up for swinging open; Fig. 12 is an inside face view of the triple motion top hinge when open; Fig. 13 is a cross horizontal section of Fig. 12 on the line 13—13; Fig. 14 is the same section with the hinge 25 closed; Fig. 15 is an inside face view of the bottom hinge; Figs. 16 and 17 are face views of the detachable and reversible leaves of the top and bottom hinges respectively, and Fig. 18 is a front and side view of a flat leaf 30 spring to be fixt in the back of the rabbet of the frame near the top and opposite the top hinge to thrust the sash out at the top when the same is lifted for opening. This member is not shown elsewhere on the drawings 35 but will be referred to in the specification.

Similar characters refer to similar parts in the several views.

Heretofore casement windows with sash 40 made to swing inwardly have been more or

less faulty because of not being rain, wind and dust proof. Outwardly swinging casement sash do not admit of outside screens usually preferred to screens inside. The invention herein set forth and described is designed to overcome these faults and provide an inwardly opening casement sash that will be tight and easily operated.

Referring to the drawing the usual form of a casement window is indicated, the frame 45 referred to as 1 and the sash as 2. In Figs. 1 and 2 the sash is shown closed and is set down tight in an outside rabbet in the window stool 3 whereby the bottom of the sash is made rain and dust-proof. The sash likewise fits tightly into the side and top rabbets of the window frame as seen at 4. The side of the sash opposite the hinged side, it will be understood, will be closed tight by a casement fastener common in casement windows. 50 It will be observed the top of the sash is rabbeted with a beveled side or lip as seen at 5 in Figs. 2, 3 and 4.

In order to operate a casement sash thus fitted, novel hinges, a lift and adjuster have 55 been devised to be used in combination with a casement sash for opening and closing the same. No one of the fixtures is a complete device in itself, but all must be used in combination with a casement sash to make 60 a complete and operative invention.

The sash lift and ventilating adjuster is shown enlarged in Figs. 6, 7 and 8. It comprises a cross bar lift handle 6 mounted on a disk 7. This disk is pivotally mounted on 65 a face plate 8 by a set screw 9 indicated at its center. Mounted on the disk 7 and extending to the rear through the face plate 8 is a stud 10 that engages a tubular foot bolt 11 in the lower end of which is tightly 70 fitted a rubber foot piece 12. This tube 11 is split on one side at 13 and is fitted to slide in a solid socket tube 14 to be fixt in the bottom of the sash 2 as indicated in 75 Figs. 1, 2 and 3. The rubber foot piece 12 so expands the split tube 11 as to cause a friction with the encircling fixt tube 14. This holds the rubber foot 12 steady when 80 turned down on the friction plate 15 shown in Figs. 5 and 8. The foot 12 is set by turn- 85

ing lift bar to the right till the stud 10 pushes the tube 11 down tight.

In order to lift the sash clear of the rabbeted stool 3, special motion hinges have 5 been devised as shown in Figs. 12, 13, 14 and 15. Each hinge is made with one usual form of leaf 16 to be screwed to the side jamb of the window frame. The opposite leaf 17 is made double and narrow 10 and so spaced apart as to admit of inserting a removable and reversible leaf plate 18 for the top hinge and 18' for the bottom hinge to be screwed to the sash. The plate 18 is provided with two inclined slots 15 19—19' through which rivet screws 20 are set through the double narrow leaf 17. The leaf plate 18' has vertical slots 19'—19' through which screw rivets are set as in the top hinge. These leaf plates are fixt to 20 the sash so as to be in alinement with the leaves 16 when the casement sash is closed the same as when the present form of hinge is used.

The sash 2 now being hung and closed 25 within the window frame as shown in Figs. 1 and 2, the sash is opened by lifting up on the sash lift bar 6. The sash leaf plates 18 and 18' will slip up between the narrow double leaves 17. The inclined slots of the 30 top hinge will thrust the top of the sash toward the interior of the building causing the beveled side or lip of the sash rabbet 5 to clear the top jamb of the window frame as shown in Fig. 3. The slots 19—19' in 35 the bottom hinge being vertical, will cause the bottom of the sash to lift straight up and thus clear the rabbet of the window stool 3. The bottom hinge is provided with a spring actuated sliding bolt 21 which is 40 designed to engage the hole 22 when raised to alinement with it. This bolt 21 will hold the sash fixed in its lifted upright position so it can now be swung wide open into the room as shown in Fig. 4, or be set at 45 any angle desired for ventilation by the sash adjuster operated by the lift bar 6 heretofore described. The spring actuated bolt 21 is shown in enlarged detail in Figs. 9, 10 and 11. This bolt has no special novel- 50 ty but is a necessary part of the operating mechanism of the casement window described herein.

In order to make the top of the sash opposite the hinged side thrust out positively, 55 a flat leaf spring shown in Fig. 18 is put in the window frame rabbet near the top of the sash and opposite the top hinge. This will cause the beveled lip to clear the top jamb when the sash is lifted.

To close the window, the sash is swung 60 shut to the position shown in Fig. 3. The spring bolt 21 is then drawn back clear of the lower leaf plate 18 and the sash pushed down into the outer rabbet of the window stool by pressing down on the bar 6 of the 65

sash lift. The sash will now be in the position shown in Figs. 1 and 2.

It will be observed the hinges can be changed from a left hand to a right hand side of the sash by removing the loose pins 70 23 and turning the leaves 16 each up end down and again fitting hinges together with the loose pins. Therefore no right and left hand hinges will be required in the manufacture of the invention as in other 75 casement window hinges. The sash lift and ventilating adjuster is also made reversible. The disk 7 can be detached and the stud 10 be taken from the radial slot indicated at *a* and set through the radial slot *b* indicated 80 on the opposite side.

It is to be further understood that the invention is not limited to exact details or proportions, but the right is reserved to vary the same to meet the requirements of 85 any form or size of casement windows.

Having described my invention, I claim—

1. In a casement window with an inwardly swinging sash, a pair of hinges, each one of said hinges having one leaf slidably 90 inserted between a short double leaf as described, the slideable leaf of the upper hinge of said pair of hinges having diagonal sliding engagement by means of diagonal slots therein with the said double leaf of said upper hinge, and the slideable leaf of the lower hinge of said pair of hinges having vertical sliding engagement by means of vertical slots therein, with the said double leaf of said lower hinge as set forth and 95 described and for the purposes set forth.

2. In a casement window with inwardly swinging sash, a pair of hinges, each one of said hinges having one leaf slidably inserted between a short double leaf as described, 105 the slideable leaf of the upper hinge of said pair of hinges having diagonal sliding engagement therewith, the slideable leaf of the lower hinge having a vertical sliding engagement therewith, and each of said slideable leaves being reversible for the purpose of using said pair of hinges on either the right or the left side of said casement window as set forth and described.

3. In a casement window with inwardly swinging sash, a pair of hinges, each one of said hinges having one leaf slidably inserted between a short double leaf as described, the slideable leaf of the upper hinge of said pair of hinges having diagonal sliding engagement therewith, the slideable leaf of the lower hinge of said pair of hinges having vertical sliding engagement therewith, and said lower hinge of said pair of hinges having means for holding the slideable leaf of the said lower hinge fixt when vertically lifted for the opening of said casement window sash, as set forth and described.
